UNITED STATES PATENT OFFICE.

OSCAR H. PIEPER AND ALPHONSE F. PIEPER, OF ROCHESTER, NEW YORK.

PRESSURE-REGULATOR.

1,304,704.

Specification of Letters Patent. Patented May 27, 1919.

Application filed September 27, 1915. Serial No. 52,937.

To all whom it may concern:

Be it known that we, OSCAR H. PIEPER and ALPHONSE F. PIEPER, of Rochester, county of Monroe, and State of New York, have invented certain new and useful Improvements in Pressure-Regulators; and we do hereby declare the following to be a full, clear, and exact description of the same, reference being had to the accompanying drawings, forming a part of this specification, and to the reference-numerals marked thereon.

Our invention has to do with pressure regulating devices of the character embodying generally a valve controlling a pressure supply, and mechanism governed by changes of pressure within a chamber for effecting movement of and determining the position of the valve, an instance of the use of such a device being found in the art of dental instruments that require a continuous supply of fluid pressure such as air, where it is desirable to maintain a more or less constant pressure which can be adjustably fixed within certain limits. A more particular purpose of the invention is to afford a construction having few parts and which can be manufactured at a minimum cost, while at the same time resulting in a combination that is both strong and efficient and will respond to the slightest changes that may be required, and will continue in operation for an indefinite period without likelihood of requiring repair or having its efficiency in any way impaired. To these and other ends the invention consists in certain improvements and combinations of parts, all as will be herein-after more fully described the novel features being pointed out in the claims at the end of the specification.

In the drawings:

Figure 1 is a vertical sectional view of a preferred embodiment of the invention.

Fig. 2 is a plan view of the lower part of the casing with the upper part removed.

Fig. 3 is a plan view showing the valve member and the coöperating parts in position.

Fig. 4 is a sectional view on line 4^a—4^a of Fig. 3, and

Fig. 5 is a sectional view on line 5^a—5^a of Fig. 3.

Similar reference characters throughout the several views designate the same part.

According to a preferred form, the invention comprises a chamber 1 formed by up-

per and lower sections of a casing 2 and 3 respectively, the upper section being suitably retained in a wall, or support 4, as by means of a nut 5 having engagement with the threaded neck portion 6 on the section 2.

Attached to the lower section 1 is a pipe 7 which leads to, or is otherwise connected with, a source of pressure supply. Arranged in the opening formed in the lower part of the casing is a sleeve 8 threaded at its upper end to receive a nipple 9 of a connection 10 which extends laterally within the chamber and affords a downwardly extending pressure inlet 11. Just above the pipe 7, there is preferably disposed an air filtering means 12 which may be in the form of a screen 12 having superposed thereon flannel, or other similar fibrous material indicated as 13, which acts to free the air from any dust particles, or other impurities.

The valve member is designated generally at 14, and comprises a plate including a widened portion 14^a which is pivotally mounted on bearings 15 fixed on the adjacent wall of the casing so as to permit the valve member to swing upon a horizontal axis. 12^a designates a seat of rubber, or other resilient material positioned in a recess of the reduced portion 14^b of the valve member, for engagement with the open end of the connection 10 so as to open and close the air inlet when required. In order to retain the valve member in its normal position, a flat, or leaf spring, is provided, which is attached to the casing and has an upstanding portion 15^a extending through an opening or cutaway portion 14^c of the valve member. A downwardly projecting edge 16 of the spring engages the upper surface of the valve member at one side of its pivotal axis, the spring being attached to the adjacent wall of the casing preferably within said cutaway portion 14^c. The valve member is arranged to be engaged by pressure controlled means on the other side of its pivotal axis in order to effect varying movements in accordance with variations in the pressure, and with this in view we employ a diaphragm 17 extending across the chamber 1 and secured between the upper and lower sections 2 and 3 of the casing. The diaphragm 17 carries a projection 18 arranged to engage the upper surface of the valve member 14 on the opposite side of its pivotal axis from where it is engaged by the aforementioned spring.

Thus, as the pressure in the chamber falls, the projection 18 moves downwardly rocking the valve member upon its axis and opening the inlet while an increase of pressure elevates the projection 18, closing the inlet correspondingly. The action of the diaphragm 17 may be varied by adjusting the tension of a spring 19 which bears on its upper side. The upper end of the spring 19 receives a follower 20 with which engages an adjusting screw 21 threaded in the cap 22.

The chamber 1 includes an outlet 23 through which the pressure medium is supplied to any desirable point through a suitable connection, which forms no part of the present invention. 24 designates a stop formed on the lower side of the valve member for limiting its downward, or opening movement, while 25 is a spring carried by the valve member and engaging the wall of the casing in a manner that causes the movement of the valve member to be steadied and controlled so as to insure an even regular adjustment.

We claim as our invention:

1. In a pressure regulator, the combination of a casing having inlet and outlet openings, a valve member pivotally supported in said casing and adapted to co-operate with said inlet opening, pressure controlled means for moving said valve member to open said inlet opening, a flat spring having a downwardly projecting edge engaging said valve member and adapted to move the valve member to close said inlet opening, and a spring on the valve member frictionally engaging a wall of the casing for controlling the movements of the valve member.

2. The combination with a casing having a pressure inlet spaced from and

directed toward one wall thereof, of a valve member pivotally mounted upon said wall of the casing and having a seat on its upper surface co-operating with the aforementioned inlet, the valve member having a cut-away portion, a leaf spring attached to said wall of the casing and extending through the cutaway portion into engagement with the upper surface of the valve member, and pressure controlled means engaging the upper surface of the valve member at a point between its pivotal axis and the pressure inlet.

3. The combination with a casing having a pressure inlet spaced from and directed toward the wall thereof, of a plurality of bearings arranged upon said wall of the casing, a valve member having a widened portion pivotally supported at opposite points of its lower surface upon said bearings and having a reduced portion provided on its upper surface with a seat co-operating with said inlet, the valve member having a cutaway portion, a flat spring attached to said wall of the casing having an upwardly extending portion projecting through the cutaway part of the valve member, and a downwardly extending portion engaging the upper surface of the valve member at its free end, and pressure controlled means engaging the upper surface of the valve member at a point between said bearings and the pressure inlet.
